REFRIGERATOR PORT FOR DISPENSING
CONTAINER AND CLOSURE THEREFOR

Eshcol S. Gross, Long Beach, Calif.

Application August 5, 1944, Serial No. 548,297

3 Claims. (Cl. 312—186)

1

This invention relates to refrigerator ports for dispensing containers and closures therefor.

Most fruit juices, vegetable juices and other beverages are dispensed from jugs or large bottles which are maintained chilled or refrigerated. It is necessary to remove the bottle or container from the refrigerator in order to dispense the desired amount of the beverage, during which time, the cooling medium escapes from the refrigerator. It is a primary object of this invention to provide a refrigerator port for beverage container that will automatically seal the port against the ingress or egress of air during the dispensing operation.

Another object is to provide a port having the above characteristics that will increase the efficiency of the refrigeration units and facilitate rapid dispensing of beverages from the container.

A further object is to provide a refrigeration unit having the above characteristics that will be durable, efficient in operation and comparatively cheap of manufacture.

The above and other objects will be made apparent throughout the further description of the invention when taken in connection with the accompanying drawings wherein like reference characters refer to like parts. It is to be distinctly understood that the drawings are not a definition of the invention, but merely illustrate one form by which the invention may be effectuated.

Fig. 1 is a side elevation through a portion of a refrigerated case illustrating a dispensing container positioned within a part of such case.

Fig. 2 is an end elevation of the arrangement shown in Fig. 1.

Fig. 3 is a side view showing the arrangements of the elements when the dispensing container is withdrawn.

In the illustrative form shown in the appended drawings, the top or wall of a refrigeration case is indicated at 10, such wall being provided with the port 11. The interior of the case is refrigerated by means of suitable coils, dry ice, water ice, or other heat-absorbing means not shown in detail since they are well known to those skilled in the art.

Attached to the lower surface of the top 10 is a spacer ring 12, the inner diameter of this ring being slightly greater than the inner diameter of the opening or port 11. Attached to the lower surface of the annular spacing ring 12 is an annular sealing gasket 13, whose inner diameter is smaller than the internal diameter of the spacer 12 and of the port 11. The internal diameter of

2

the gasket 13 is slightly smaller than the outside diameter of a dispensing container such as the jug 14 shown in phantom lines. The inner edge portions of the gasket 13 are preferably resilient and flexible so as to yieldingly grasp the dispensing container 14 and conform to whatever irregularities of contour may exist in the jug 14.

Suspended within the refrigeration case from the wall or top 10 is a U-shaped yoke or frame which in the illustrative embodiment comprises the upstanding legs 15 and 16 and the connecting bottom portion 17. This yoke may be attached to and carry the spacer ring 12. The yoke is attached to the lower surface of the wall or top 10 with the legs 15 and 16 on opposite sides of the port 11 so that the bottom portion 17 of the yoke extends transversely across downward projection of the port.

A supporting plate 18 which may be circular in shape and having its outer edge terminating in an upstanding annular flange 19 is movably positioned within the yoke and is preferably in slidably guiding contact with the yoke. In the form shown, each of the upstanding legs of the yoke is provided with a vertical slot such as the slot 20 in leg 16. Pins 21 and 22 are carried by the supporting member 18 and slidably extend through the slots 20 in the legs of the yoke. A downward extending shaft or guide-rod 23 is attached to the supporting member 18 and extends through an aperture in the horizontal member 17. Spring means 24 are interposed between the portion 17 and the bottom of the supporting member 18, thereby yieldingly urging the supporting member towards the port or aperture 11.

It will be noted that while the dispensing container or jug 14 is supported by member 18 and extends partly through the port 11, the gasket 13 is in resilient yieldable contact with the surface 40 of the container 14 and thereby prevents egress of cold air from the refrigerator. When the dispensing container 14 is withdrawn, the supporting member 18 rises to bring the peripheral edge of the flange 19 into sealing contact with the gasket 13 so as to form a tight closure for the port or opening. It is to be understood that the upward movement of the supporting member 18 is attained by means of the spring 24 and that the diameter of the supporting member 18 is 45 sufficiently large so as to completely cover the opening 11, through which the dispensing container 14 has been withdrawn.

The support 18 is preferably circular in shape and its outer edges terminate in a continuous upwardly extending flange. The upper edge of

the continuous flange of the support comes into contact with the annular gasket to seal the opening while the inner edge portion of a gasket is still in contact with the container.

In the form of device illustrated, the spring 24 is completely collapsed and assists in supporting the dispensing container when a full dispensing container is placed within the case as shown in Fig. 1. Obviously the condition of the spring depends somewhat upon its strength and the weight to be supported. The springs for yieldably urging the supporting plate 18 towards the opening may be attached to the lugs or pins 21, 22 and to the lower surface of the top 10, and need not be positioned around the guide shaft 23. When the alternative positioning of the springs is used the shaft 23 may be dispensed with.

The yoke or frame is preferably attached to the lower surface of the top wall (thereby not interfering with the effective use of the lower part of the case), but it may also be a frame supported in any other manner. The yoke may have two, three or four upwardly extending legs. The supporting plate may be flat or dished. The sealing gasket may be of rubber, rubber-like composition, leather or any other suitable flexible material.

In the illustrated form of device, the annular ring 12 is of greater internal diameter than the internal diameter of gasket 13 or port 11, and acts as a spacer between the top 10 and the gasket 13, thereby preventing the gasket from "pinching" or "blocking" when a bottle is being withdrawn. The gasket may, in some instances, be used directly on the upper surface of top 10; in other instances the spacing ring 12 may be eliminated. Moreover, the upper edge or edge portion of support 18 may be provided with a separate seating ring or bumper to assure complete sealing when the support is at the upper end of its stroke, as in Fig. 3.

All changes which may occur to one skilled in the art are embraced by the appended claims.

I claim:

1. A device of the character described, including a top wall for an enclosure, a port in said wall for receiving a container, a frame depending from said top wall and beneath said port; a support mounted in said frame and adapted for vertical movement relative to said frame, means for at-

taching and guiding said support in said frame, the said support being of greater area than said port and adapted to close the said port when said container is removed from said port; spring means of sufficient strength to elevate the said support to close the said port and with insufficient strength to support the said container on the support when the latter is in closing position; sealing means carried by said wall and positioned beneath and adjacent the edges of said port, said sealing means consisting of a gasket and a spacer between the said gasket and the lower surface of said wall, the said gasket having a fixed portion for forming a seal with said support, and a yieldable inner edge portion extending into the path of said container for forming a seal with said container.

2. A device in accordance with claim 1 wherein the said port is circular and the said spacer and gasket are annular and position concentrically with said port.

3. A device of the character described, including a top wall for an enclosure, a port in said wall for receiving a container, a frame depending from said top wall and beneath said port, a support mounted in said frame and adapted for vertical movement relative to said frame, means for attaching and guiding said support in said frame, the said support being of greater area than said port and adapted to close the said port when said container is removed from said port, the edges of said support terminating in a continuous upwardly extending flange, the upper edge of the continuous flange arranged to contact the gasket at a level substantially above the supporting plane of the support of the container.
